UNITED STATES PATENT OFFICE

138,217

DESIGN FOR AN AIRPLANE

Willem D. van Zelm, Ruxton, Md., assignor to The
Glenn L. Martin Company, Baltimore, Md.

Application August 20, 1942, Serial No. 107,982

Term of patent 14 years

(Cl. D71—1)

To all whom it may concern:

Be it known that I, Willem D. van Zelm, a citizen of the United States and a resident of Ruxton, in the county of Baltimore and State of Maryland, have invented a new, original, and ornamental Design for an Airplane, of which the following is a specification, reference being had to the accompanying drawings, forming part thereof.

Figure 1 is a top plan view of the subject airplane,

Figure 2 is a front elevational view of the airplane shown in Figure 1.

Figure 3 is a side elevational view of same.

Figure 4 is a bottom perspective view of the airplane as it appears with the landing gear retracted.

I claim:

The ornamental design for an airplane, substantially as shown.

WILLEM D. VAN ZELM.
